UNITED STATES PATENT OFFICE

2,525,883

ELECTRIC LADLE FURNACE

Vernon H. Ferguson, Mount Lebanon, Pa., assignor to Loftus Engineering Corporation, a corporation of Maryland

Original application May 14, 1949, Serial No. 93,243. Divided and this application January 21, 1950, Serial No. 139,896

2 Claims. (Cl. 13—21)

1

My invention relates to furnaces, particularly to ladle furnaces for use in handling molten metal in foundries and other industrial shops.

A ladle furnace of the sort in mind consists in a crucible for molten metal. The crucible is installed within a refractory-lined body or shell, with a space provided between the walls of the crucible and the shell for electrical heating elements (or for hot products of combustion) to heat and maintain the molten metal within the crucible at desired temperature. The entire structure is adapted to be pivotally supported by means of a bail that can be engaged by an overhead crane, or the like, and on such pivotal support the ladle structure is arranged to be tilted, whereby molten metal may be poured or teemed from the crucible as required.

My invention consists in certain new and useful structural improvements in ladles or ladle furnaces of this type, to the end that thermal efficiency is obtained in largest measure, together with increased economy and durability of structure.

From time to time the crucibles of such ladles fail in service, with the result that molten metal escapes into the space within the refractory-lined body or shell. This requires that the ladle structure be taken out of service and the molten metal, then solidified, removed. This is the difficult task, and in the case of electrically heated ladles, there is danger of destroying or damaging the heating elements.

In further accordance with the objects of my invention, I provide a false bottom on the refractory-lined body or shell. This false bottom is arranged at an interval below the normal refractory-lined bottom of the shell, providing an auxiliary chamber. Passages are formed in the normal bottom of the refractory-lined body and these open into the auxiliary chamber, whereby molten metal (escaping due to the failure of the crucible) runs into the auxiliary chamber where it is accumulated and solidified. The false bottom is readily dismountable, for the removal of the solidified metal.

In the accompanying drawings a ladle furnace comprising an exemplary embodiment of the invention is illustrated in the drawings:

Fig. 1 is a view of the ladle furnace in front elevation;

Fig. 2 is a sectional view of the ladle furnace, as seen on the plane II—II of Fig. 1;

Fig. 3 is a diagrammatic view of a mechanism included in the structure for manually tilting the ladle on its pivotal support;

2

Fig. 4 is a view in medial horizontal section through the ladle, illustrating a modification in structure;

Fig. 5 is a view partly in side elevation and partly in vertical section of a ladle embodying still other modifications in structure; and

Fig. 6 is a fragmentary view in vertical section, showing the lower portion of the modified ladle structure of Fig. 5 to still larger scale.

10 Referring to the drawings, the ladle structure comprises an outer shell 2, cylindrical in this case, formed of steel plate. Above the center of gravity of the ladle structure, trunnions 3 are secured upon opposite sides of the shell in axial alignment, and to these trunnions a bail 4 is attached, the bail having an eye 5 whereby the entire structure may be engaged, lifted and transported by means of an overhead crane.

On one side of the ladle a hand-wheel 6 is 20 geared to the adjacent trunnion 3, by means of which the ladle structure, when suspended from a crane, may be manually tilted, to pour or teem molten metal from a spout 7, as will presently appear. The gearing between the hand-wheel 6 and the adjacent trunnion 3 consists in a worm-gear 8, a worm 9, and two bevel gears 10 and 11. The bevel gear 11 is integral with the axis of the hand-wheel 6, and meshes with the bevel gear 10 which is rigidly mounted on a shaft 12 that carries the worm 9 meshing with the worm-gear 8. It will be manifest that the rotation of the hand-wheel in either direction will effect rotation of the worm-gear 8 with great mechanical advantage, and, the worm-gear 8 being rigidly secured 30 on the adjacent trunnion 3 of the ladle, the ladle may be tilted as required. The engagement of the teeth of the worm 9 with the teeth of the worm-gear 8 serves as a mechanical lock to prevent the tilting of the ladle from any position 35 into which the ladle is adjusted.

A refractory lining 13 is provided within the body or shell 2, the refractory lining or partition at the bottom of the body being borne on a plate 14 secured to an annulus 15 of angle shape in 40 cross-section, welded to the steel plate which forms the outer shell of the structure.

In the refractory-walled chamber 16 thus provided, a crucible or pot 17 is mounted, the body of the crucible being formed of refractory ceramic material, or metal, depending upon the nature of the metal to be maintained in molten condition in the crucible. The crucible is supported on a stool 18 constructed of steel alloy or other suitable heat-resisting, heat-conducting material, in this case the stool being formed of a

25% chrome-12% nickel steel alloy. It will be noted that the stool consists in an open ring portion 19, upon which the crucible immediately seats, and from said ring portion a plurality of spaced legs 20 extend downward through the refractory floor of the chamber 16 to the metal plate 14 that forms the normal bottom wall of the chamber.

Over the top of the structure a refractory-lined metal cover 21 is removably secured by means of screws 22.

The means for melting, heating and maintaining a charge of metal within the crucible 17 in the desired molten condition consists in electric resistor elements 23 supported on insulators 24, which protrude inwardly from the refractory wall or lining 13 into the space provided between such lining and the wall of the crucible. Electrical cable 25 carries from a suitable source electric current to the resistor elements 23, and in known way such elements are energized to generate the required heat. It will be noted that the stool is of open construction, providing a passage beneath the crucible, whereby the heat generated within the chamber 16 will be distributed and applied uniformly over all of the surface areas of the crucible.

The refractory-lined body 2 is provided with a false bottom 26 which is spaced at an interval below the normal refractory bottom of the chamber 16. The bottom 26 consists of a heavy plate of steel welded to an annulus 27 of angle shape in cross-section, and is secured to the outer shell 2 by means of removable screws 28 passing through the vertical flange of said annulus into threaded engagement with shell 2. This structure provides an auxiliary chamber 29 below the chamber 16 in which the crucible is positioned. From the chamber 16 downwardly divergent passageways 30 open into the auxiliary chamber 29. If and when the crucible 17 cracks or wears through in service, the escaping molten metal quickly flows through the passages 30 into the auxiliary chamber 29. In this way the molten metal does not accumulate in the chamber 16 where it may contact and short-circuit the resistors 23. Furthermore, if and when the crucible fails in service, the resistors 23 are de-energized to allow the structure to cool to the extent necessary to insert a new crucible. But for the improvements of my invention the escaping molten metal would accumulate and solidify in the bottom of the chamber 16, thereby presenting a difficult problem. However, in the structure described, the molten metal (regardless of the degree of tilt of the ladle structure when failure of the crucible may occur) runs into the chamber 29, where it solidifies.

The false bottom 26 of the auxiliary chamber 29 comprises a removable wall section, it being merely necessary to remove the screws 28 and remove the false bottom and dislodge the accumulated metal. The ladle may be quickly reconditioned for continued service.

In the case of certain metals, there may be a tendency for the metal to stick or adhere upon solidification to the walls of the auxiliary chamber 29. In prevention of this, the auxiliary chamber is lined with a refractory and readily separable or frangible material, such as sheet asbestos 31. When a mass of accumulated metal has been removed from the auxiliary chamber, the deciduous lining 31 may be readily renewed.

Such is the construction of a ladle furnace of my invention. The top 21 is readily removable

for charging molten or pig metal into the crucible 17, or for giving access to the internal parts of the structure for cleaning or repair. It is unnecessary to dwell upon the manner in which the ladle furnace is operated. Those skilled in the art will readily understand. Suffice it to say, that a batch metal may be melted and alloyed by the introduction of a suitable charge into the crucible, and, when in molten condition, the metal may be maintained at specified temperature for the intended use.

While the ladle structure described above is arranged for electrical heating of the crucible, in modification the structure may be designed for heating by means of a fluid fuel. As shown in Fig. 4, the chamber 16 between the refractory lining 13 of the outer body and the wall of the crucible 17 may comprise a combustion chamber, and through the shell 2 and refractory lining 13 one or more burners 32 may be directed, tangentially as shown in Fig. 4. A mixture of gaseous or liquid fuel and combustion air may be delivered by the burners 32, and combustion maintained in the chamber 16 at the desired rate, to heat and maintain the metal in the crucible at proper temperature. The products of combustion may be vented through one or more ports 33 formed in the wall of the refractory-lined body of the ladle structure.

Whereas the ladle structure first described in the foregoing specification is provided with electrical resistor elements mounted in the space between the refractory wall of the ladle chamber and the wall of the crucible, in the modified structure of Figs. 5 and 6 the resistor elements 32a are embedded in refractory units 24a, and the leads from the resistor elements 23a are extended downward through the refractory bottom of the structure, ending in terminals 34 which are accessible in an annular raceway 35 (Fig. 6). Such organization of electric resistor elements within a refractory-supporting structure is old, and forms no part of my invention, except in the features of organization of such elements with the ladle structure in which they are described.

In the modified structure of Figs. 5 and 6, it will be noted that the crucible 17a is supported upon the refractory bottom of the ladle body; that is, the legs 26a which carry the crucible-supporting ring 18a of heat-resisting alloy are fixed at their lower ends to a ring 29b which rests upon the refractory bottom.

The false bottom 26a (Fig. 6) is removably secured by screws 28a to an annulus 27a of angle shape in cross section. An angle-shaped annulus 36 is welded to the lower edge of the shell 2a, and a plurality of vertical legs 37, also of angle shape in cross section, are welded to the annuli 27a and 36, whereby a rigid support is furnished for the false bottom 26a.

A conical wall 38 is welded at its upper edge to the bottom plate 14a of the structure, and at its lower edge is welded to the inner periphery of the annulus 27a. The auxiliary chamber 29a, which is adapted to receive the escaping molten metal in case of crucible failure, is formed by the bottom plate 14a, the conical or vertically extending wall 38 and the false bottom 26a. Between the annuli 27a and 36, an outer wall or cover plate 39 extends circumferentially of the ladle structure. The cover plate 39 may be formed in sections, secured by means of screws 40 to the angle members 37. It will be perceived that an annular raceway 35 is thus formed between walls 38 and 39, and between the bottom 14a of the cru-

cible chamber and the false bottom 26a and annulus 27a, a raceway which is entirely enclosed, to form a housing for the electrical conductors (not shown) which connect the terminals 34 of the resistors 23a to the contact members of a conventional plug-in receptacle 41, by means of which the electrical feeder lines for energizing the resistors may be readily connected or disconnected. The enclosed raceway 35 may be opened for inspection or repair of the electrical conductors and housed therein, by merely removing the cover plate 39.

The auxiliary chamber 29a provides, as in the structure first described, a safe accumulation space for molten metal that escapes in the case of failure of the crucible. It is a simple matter to remove the false bottom 26a and clean away the molten metal when it has solidified.

Within the terms of the appended claims various modifications and changes in the ladle structure may be made by the mechanic without departing from the spirit of the invention.

The application to these Letters Patent comprised a division of my application Serial No. 93,243, filed May 14, 1949.

I claim:

1. A ladle furnace for molten metal comprising a crucible chamber having side walls and a bottom lined with refractory material, a crucible for molten metal supported in said chamber, electrical means arranged within the refractory walls of said chamber for heating the crucible to maintain the contents thereof in molten condition, an auxiliary chamber below said crucible chamber, said auxiliary chamber having an outer peripheral wall and a false bottom, an inner periph-

eral wall in said auxiliary chamber spaced from the outer peripheral wall of such chamber and extending between the bottom of said crucible chamber and said false bottom and forming between said outer peripheral wall of said auxiliary chamber and said bottoms a raceway for electrical conductors, means for removably securing said false bottom to the ladle structure, and a port opening through the refractory bottom of said crucible chamber into the space within said inner peripheral wall in said auxiliary chamber.

2. The structure of the next-preceding claim wherein the outer peripheral wall of said auxiliary chamber comprises a cover plate removable to give access to said raceway, and means for detachably securing said cover plate in assembly with the ladle structure.
